Primary Examiner—Bernard Ansher*Assistant Examiner*—R. Barkai*Attorney, Agent, or Firm*—Lloyd F. Seebach**[57] CLAIM**

The ornamental design for a contact lens manipulator tip, as shown and described.

DESCRIPTION

FIG. 1 is a front elevational view of a contact lens manipulator tip showing my new design;
FIG. 2 is a right side elevational view thereof, the left side elevational view being identical;
FIG. 3 is a top plan view thereof;
FIG. 4 is a bottom plan view thereof; and
FIG. 5 is a horizontal sectional view taken along the line 5—5 in FIG. 1.
